US0D1053900S

(12) **United States Design Patent** (10) Patent No.: **US D1,053,900 S**
(45) Date of Patent: ** Dec. 10, 2024

(54) **DISPLAY SCREEN WITH GRAPHICAL USER INTERFACE**

(71) Applicant: **IGT**, Las Vegas, NV (US)

(72) Inventors: **Stephanie Quiles**, Herndon, VA (US);
Derick Rougeau, Sparks, NV (US);
Steve Richardson, Round Rock, TX
(US)

(73) Assignee: **IGT**, Las Vegas, NV (US)

(**) Term: **15 Years**

(21) Appl. No.: **29/920,632**

(22) Filed: **Dec. 12, 2023**

(57) **CLAIM**

The ornamental design for a display screen with graphical user interface as shown and described.

DESCRIPTION

The FIGURE is a front view of a display screen with graphical user interface of our new design.

The broken lines showing a display screen and elements of the graphical user interface illustrate portions of the article and form no part of the claimed design.
